UNITED STATES PATENT OFFICE

HERSCHEL E. PATTON, OF GRANGEVILLE, IDAHO

PIPE CRIMPING DEVICE

Application filed March 18, 1930. Serial No. 436,856.

This invention relates to crimping devices and more particularly to a crimping device adapted for use in crimping of pipe or the like.

5 An object of this invention is to provide a pipe crimping device of this character by means of which the free ends of a section of metal may be securely fastened together.

Another object of this invention is to provide 10 a simple device wherein a section of pipe is adapted to be inserted, the metal having the free ends thereof partially turned over or bent, the device being adapted to securely press the free ends together so as to form a 15 cylindrical elongated pipe section of any desired length.

A further object of this invention is to provide 20 in a device of this character, tensioning means by which the tension upon the crimping bar may be varied to suit the particular gauge of metal which is being formed into a pipe section.

A still further object of this invention is to provide 25 a device of this character which may be manually operated but which is so constructed that the pipe section will be securely crimped with one operation of the device.

The above and various other objects and 30 advantages of this invention will in part be described and in part be understood from the following detailed description of the present preferred embodiment, the same being illustrated in the accompanying drawings wherein:

Figure 1 is a fragmentary detail side elevation of a device constructed according to the preferred embodiment of this invention;

Figure 2 is a sectional view taken on the 35 line 2—2 of Figure 1;

Figure 3 is a vertical section partly in detail taken substantially through the center of the device; and

Figure 4 is a vertical section taken on the 40 line 4—4 of Figure 1.

Referring to the drawings wherein like numerals of reference designate corresponding parts throughout the several views, the numeral 10 designates generally a base of 45 suitable dimensions which may be construct-

ed of any desired material such as wood, metal or the like and is preferably provided with a pair of end members 11 and a pair of spaced side members 12 which are provided with cut out end portions for countersinking the 55 ends of the side members in recesses 13 in the end members 11.

The opposite ends of the side members 12 may be bolted as by bolts 14 or the like to the end members 11 although, if desired, the base 60 10 may be cast in a single unit or formed of concrete or any other suitable material.

A bed 15 is mounted upon the base 10, the bed 15 comprising a substantially rigid construction and is preferably constructed of 65 metal and may be secured to the base 10 by means of bolts 16 or the like. The bed 15 is preferably provided with a longitudinally disposed slot or recess 17 which extends 70 downwardly therethrough for purposes 70 which will be hereinafter described.

A vertically disposed standard or supporting member generally designated as 18 is mounted upon the base 10 adjacent one end thereof, the standard 18 comprising a pair 75 of vertically positioned supports 19 which are bolted or otherwise secured to the base 10 by bolts 20 or the like intermediate the side members 12, and the vertically disposed supports 19 are preferably positioned upon the 80 opposite sides of the crimping bed 15.

A transversely disposed bar or member 21 is secured to the vertical supports 19 adjacent the upper end portion thereof by means of 85 bolts 22 or the like.

A stationary or fixed crimping member 23 is secured at the lower end by means of bolts or securing members 24 to the crimping bed 15, and the lower end portion of the fixed crimping member 23 is preferably positioned 90 within the elongated slot 17. The fixed crimping member 23 is also secured to the vertical supports 19 by means of bolts 25 which are positioned in the fixed crimping member 23 at a point spaced downwardly 95 from the upper end portion thereof, the bolts 25 extending horizontally through the vertically disposed crimping member 23 and being preferably positioned in the transverse member 21. 100

A movable or swinging crimping bar 26 is slidably positioned at the lower end thereof within the slot 17, the lower end portion of the swinging crimping member 26 being preferably restricted as at 27 so as to provide a flange or ledge 28 which is adapted to slidably engage the upper face portion of the crimping bed 15.

A resilient or tensioning member 29 is mounted in the bed 15 being positioned at one end in a socket or recess 30 and is adapted to engage the lower restricted end portion 27 of the swinging crimping member 26 so as to constantly urge the lower end portion thereof toward the fixed or stationary crimping member 23.

If desired, suitable adjustable means may be provided for the tensioning member 29 so that the tension on the crimping member may be varied to suit the particular purposes or to meet the varying conditions due to the fact that pipe sections of different gauges of metal are being crimped or secured together.

The inner face of the fixed crimping member 23 is provided with a concave or grooved portion 31, and the inner face of the movable crimping member 26 is preferably convex as at 32 so as to register with the concave portion 31 in the fixed crimping member 23, the concave portion 31 and the convex portion 32 being formed on an arc or segment of a circle approximately the circumference of the section pipe.

The inner face of the movable crimping member 26 in addition to being convex as at 32, is also eccentrically formed as at 33 so that when the lower end portion of the movable crimping member is in contact with the lower end portion of the fixed crimping member, the upper end portion of the movable crimping member will be positioned in spaced relation to the upper end portion of the fixed crimping member.

A pair of swingingly mounted link members 34 are secured at one end to the opposite sides of the fixed crimping member 23 adjacent the upper end portion thereof by means of a pivotal bolt 35 or the like, and the upper end portion of the stationary crimping member 23 is preferably restricted as at 36 so that the swinging movement of the link members 34 will be limited, the outstanding portion of the fixed crimping member serving the purpose of a stop or restricting member for limiting the swinging movement of the links 34.

A lever generally designated as 37 is swingingly mounted between the link members 34 by means of a pivotal bolt 38, the outer end portion of the lever 37 being formed into a handle 39, and the inner end portion of the lever 37 being formed as an eccentric 40.

The movable crimping member 26 is also provided with a stop or link limiting portion 41 adjacent the upper end portion there-

of so that when the links 34 swing downwardly and upon the opposite sides of the movable crimping member 26, the links will be limited in their downward swinging movement.

The eccentric portion 40 of the lever 37 is adapted to engage the outer edge portion of the movable crimping member 26 and when the handle 39 is pulled downwardly, the movable crimping member will be forced inwardly against the fixed crimping member 23, the movement of the movable crimping member being in the nature of a rocking movement due to the eccentric construction of the movable member 26 on the inner edge portion thereof. The lower end portion of the movable member 26 may be provided with a slot 44 therethrough, and a bolt or the like 45 may be mounted in the bed 15 and loosely engage in the slot 44 for retaining the movable member in the bed.

In the operation of this device, the lever 37 is preferably swung upwardly so as to permit the swinging crimping member 26 to be free, it of course being understood that the upper end portion of the crimping member 26 is free, whereupon a pipe section 42 is positioned between the fixed member 23 and the movable member 26, the joint of the pipe being positioned within the concave portion 31 of the fixed member 23.

It will of course be understood that prior to the insertion of the pipe section 42 between the crimping members 23 and 26, the free ends or edges of the pipe section are initially bent or reverted as at 43, and the bent edges of the pipe section are loosely hooked together.

When the pipe section 42 is positioned between the crimping members 23 and 26, the lever 37 may be swung downwardly so that the eccentric portion 40 will engage against the outer edge portion of the movable crimping member whereupon the lever may be pressed or swung downwardly so as to force the movable crimping member 26 into contact with the inner periphery of the pipe section, the movement of the swinging member 26 firmly pressing the reverted ends 43 of the pipe together so that the edges of the pipe will be firmly secured together.

It will of course be understood that various changes and modifications may be made in the details of construction and design of the above specifically described embodiment of the invention without departing from the spirit thereof, such changes and modifications being restricted only by the scope of the following claim.

What is claimed is:—

A crimping device of the character described comprising a base, a fixed crimping member mounted on the base, said fixed member having a concave inner edge portion, a rockable crimping member, said rock-

able member having a horizontally disposed slot in the lower end thereof, said rockable crimping member having a convex eccentric inner edge portion whereby to rockably clamp an annular article within the concave inner edge portion of said fixed member, resilient means engaging the lower end of said rockable member whereby to constantly urge the lower end toward said fixed member, and an eccentric lever swingingly carried by said fixed member and adapted for engagement with said rockable member whereby to position said rockable member against said fixed member.

In testimony whereof I hereunto affix my signature.

HERSCHEL E. PATTON.
